Primary Examiner—Louis S. Zarfas*Assistant Examiner*—John Windmuller*(74) Attorney, Agent, or Firm*—Kolisch Hartwell, P.C.(57) **CLAIM**

I claim the ornamental design for a packaging tie-down, as shown and described.

DESCRIPTION

FIG. 1 is an isometric top view of a packaging tie-down according to the present invention.

FIG. 2 is an isometric bottom view of the packaging tie-down of FIG. 1.

FIG. 3 is a top view of the packaging tie-down of FIG. 1.

FIG. 4 is a bottom view of the packaging tie-down of FIG. 1.

FIG. 5 is a rear view of the packaging tie-down of FIG. 1.

FIG. 6 is a front view of the packaging tie-down of FIG. 1.

FIG. 7 is a left side view of the packaging tie-down of FIG. 1; and,

FIG. 8 is a right side view of the packaging tie-down of FIG. 1.
